UNITED STATES PATENT OFFICE.

CHARLES ARTHUR JACOBS, OF TOLEDO, OHIO, ASSIGNOR TO BENJAMIN F. MILLER AND WILLIAM W. BOWES, OF SAME PLACE.

STEAM-ENGINE.

SPECIFICATION forming part of Letters Patent No. 317,541, dated May 12, 1885.

Application filed November 21, 1884. (No model.)

To all whom it may concern:

Be it known that I, CHARLES A. JACOBS, a citizen of the United States, residing at Toledo, in the county of Lucas and State of Ohio, have 5 invented a new and useful Improvement in Steam-Engines, of which the following is a specification, reference being had to the accompanying drawings.

My invention relates to engines designed to 10 be driven by either steam or water; and it has for its object to provide a machine of this character which shall possess superior advantages in point of simplicity, durability, inexpensiveness, and general efficiency.

15 With these ends in view the said invention consists in the improved construction and novel combination of parts, as will be herein-after fully set forth, and particularly pointed out in the claims.

20 In the accompanying drawings, Figure 1 is a longitudinal vertical section on the line *xx*, Fig. 2. Fig. 2 is a plan view of the same. Fig. 3 is a transverse sectional view on the line *yy*, Fig. 1. Fig. 4 is a detail horizontal section, taken through the parts of the cylinder, showing the slide-valve.

Like letters are used to indicate corresponding parts in the several figures.

Referring to the drawings, A designates the 30 cylinder, which is provided with externally-threaded open ends B B', and at its center is formed with a vertical integral partition, C. On opposite sides of the said partition the cylinder is provided with two straight ports,

35 C' C², which communicate with the steam or water chest S. An exhaust-port, e, is located between the ports C' C², and is provided with an outlet, D, which may be curved down through the frame-work of the engine, as 40 shown in Fig. 3, or extend in a vertical line down through the same.

F F' designate the pistons, which work through the open ends of the cylinder on opposite sides of the partition C, and are bored 45 out so as to be made hollow. The outer ends of the pistons are left open, while the inner ends are closed, so that the steam or water entering the cylinder through the respective ports C' C² may act against the closed ends of 50 the pistons to work the latter forward.

E is a connecting-rod, to the ends of which the pistons are secured by jam-nuts. This rod works in a passage bored through the partition C, and is made steam and water tight in the said passage by a stuffing-box, G.

55 On the ends B B' of the cylinder are secured the stuffing or packing boxes l m, which screw over the threaded ends B B', said boxes being reduced in diameter at the outer half thereof to fit the pistons sufficiently to serve as guides, 60 and at the same time allow free movement when in operation.

J designates the connecting-rod, secured at one end by a wrist-pin, B³, to the crank-wheel B² on the driving-shaft B⁶, and at the other 65 end to the piston F' by a pin, B⁴. The rod O² is connected at one end with an eccentric on the driving-shaft B⁶ to receive movement therefrom, and at the opposite end with a slide-valve, P, which moves in the steam or 70 water chest S (see Figs. 3 and 4) over the ports C' C², to alternately make communication between either of the ports and the exhaust-port e.

75 It is optional in this class of engines whether a governor be employed or not. I have illustrated one in the drawings; but it is not absolutely essential. When a governor is used, it is driven by a band, Z, connecting with the drive-wheel, the water or steam entering the 80 cylinder through the governor. Otherwise the water or steam enters directly through the water or steam chest S.

The operation of my invention will be readily understood from the foregoing description, 85 taken in connection with the annexed drawings.

It will be observed that the steam or water in the chest S is caused to act alternately upon the inner ends of the pistons. By the peculiar 90 connection of the latter one piston, F, is moving out under the action of the steam or water, while the other piston, F', is working in to exhaust the steam from that end of the cylinder.

95 It will be understood that the relative connection of the eccentric O² and the connecting-rod J is such that as the former moves backward to actuate the valve P and open the port C', and cause communication to be made be- 100

tween port C^2 and the exhaust-port e , the latter (rod J) is moved forward to slide the pistons $F F'$. By this action the steam or water from the chest enters the port C' and acts upon 5 the inner end of the piston F , while the steam or water within the other end of the cylinder is pushed or forced by the piston F' through the port C^2 and exhausts out through the outlet D . In the forward movement of the eccentric-rod O^2 the action of the parts is just 10 the reverse, the piston F exhausting through the port C' , while the piston F is driven forward in the cylinder by the steam or water entering the port C^2 . In this construction of 15 engines the water or steam plays upon the inner ends of the plungers or pistons, and not upon the outer ends, as in other machines.

It will be observed that the stuffing-box G serves to prevent the steam or water passing 20 from one end of the cylinder to the other. The partition C is perfectly solid, with the exception of the bore or passage in the center for the connecting-rod E to work through. This connecting-rod may be fitted to the pistons, as shown; or it may be cast solid with 25 the piston F' , and the other piston F made with a threaded opening to screw on the rod. By extending these hollow pistons $F F'$ out from the cylinder they form their own guides, 30 and this, in connection with the stuffing-boxes $l m$, enables the engine to work evenly and with less friction and wear on the parts.

In order to define the nature, scope, and 35 advantages of the present invention, I would have it understood that steam-cylinders with open ends are old; that hollow pistons are not broadly new, and that it is old to construct an engine with double pistons which are worked backward and forward in their respective cylinders, steam being supplied to one cylinder 40 while it is being exhausted from the other cylinder. Therefore, I lay no claim to either of these constructions, but base my improvement on the novel construction and combination of 45 the several parts, whereby the engine is simplified and the working is made more efficient in every respect.

Having described my invention, what I 50 claim as new, and desire to secure by Letters Patent, is—

1. The combination, with the cylinder A , open at each end, and provided with a partition, C , cast integral therewith at the center, of

the hollow pistons $F F'$, working in the cylinder on each side of the partition, and extended beyond the open ends of the cylinder, a connecting-rod, E , working in a passage provided through the partition and connecting the two pistons together, a steam or water chest, S , ports $C' C^2$, communicating with the latter, and 60 opening into the cylinder on opposite sides of the partition, the slide-valve P , and the exhaust-port located between the ports $C' C^2$, for the purpose set forth.

2. The cylinder A , open at each end, and 65 provided with a central partition, C , in combination with the pistons $F F'$, working in the cylinder on each side of the partition, a rod, E , connecting the pistons and working in a passage provided through the partition, the 70 steam or water chest, slide-valve, the steam-ports $C' C^2$, affording communication between the steam-chest and the cylinder on opposite sides of the partition, and the exhaust-port e , located between the steam-ports, whereby the 75 steam is caused to act against one piston in one section of the cylinder and to be exhausted by the other piston from the other section thereof, for the purpose set forth.

3. The cylinder A ; open at each end, and 80 provided with a partition, C , cast integral therewith, in combination with the hollow pistons $F F'$, working in the cylinder on each side of the partition, and extended beyond the open ends of the cylinder, the inner ends 85 of the pistons being closed, the rod E , connecting the pistons, and working in a passage provided through the partition, a stuffing-box, G , fitting in the latter around the connecting-rod, stuffing-boxes $l m$, screwing over the threaded 90 ends $B B'$ of the cylinder, and reduced in diameter at the outer ends to fit the pistons and act as guides therefor, the steam or water chest S , the slide-valve P , the ports $C' C^2$, opening 95 into the cylinder on opposite sides of the partition, an exhaust-pipe, e , located between the ports $C' C^2$, and an outlet, D , for the exhaust-port, for the purpose set forth.

In testimony that I claim the foregoing as my own I have hereto affixed my signature 100 in presence of two witnesses.

CHARLES ARTHUR JACOBS.
